DOOR HOLDER

Enoch J. Blackmon, Sherman, Tex.

Application April 5, 1945, Serial No. 586,730

2 Claims. (Cl. 16—66)

1

This invention relates to new and useful improvements in door holders.

One object of the invention is to provide an improved device adapted to be applied to a door frame and connected with a door for causing actuation of the door to closed position.

An important object of the invention is to provide a door holder of the character described which is so arranged that it will restrain the door in an open position when said door is opened past a right angle with the door frame or casing.

A further object of the invention is to provide a door holder having resilient means for causing actuation of the door and wherein the action of the resilient means is "snubbed" or resisted by air suction means incorporated in the holder.

A particular object of the invention is to provide an improved door holder wherein the actuating mechanism is so pivoted with respect to the door frame and door that the force exerted by the actuating means normally acts to urge the door to closed position, but when the door is opened past a predetermined angle, such mechanism acts to hold the door open.

Another object of the invention is to provide a door holder which is simple in design and construction and which may be readily attached to substantially any type or size of door for causing actuation thereof.

Additional objects and advantages of the invention will be apparent from the reading of the following description of a device constructed in accordance with the invention, and reference to the accompanying drawings thereof, wherein:

Figure 1 is a view, in elevation, of a device constructed in accordance with the invention and showing the same in operative position on a door and door frame.

Figure 2 is an enlarged view, partly in elevation and partly in section, of the door holder mechanism, and

Figure 3 is an enlarged isometric view of the holder plate.

In the drawings, the letter A designates an angular holder plate adapted to be secured at one end to a door frame by screws or other suitable means and having a pivot opening located centrally of its outer end. The opening is positioned in a plane extending through the door hinges and vertically of the door frame.

An elongate cylindrical housing D is pivotally connected at one end to the holder plate by means of a hinge bolt B so as to be swingable in a horizontal plane. The pivoted end of the housing is closed by a cap C, which may have a lubricated

packing (not shown) secured thereto for lubricating the hinge bolt B. The free end of the housing is also provided with a cap member E having an axial opening therein through which an elongate reciprocating rod F extends into the housing.

A helical coiled spring J surrounds the rod F within the housing and has one end secured within an opening in the wall of the housing near the cap member E. The other end of the spring is fastened to the reciprocating rod at a projection I near its inner end, as clearly shown in Figure 2. It will be seen, therefore, that the spring exerts its tension to constantly urge the rod outwardly from within the housing. The projection I on the reciprocating rod, by means of which the spring is connected to the reciprocating rod, is preferably a nut threaded onto the end of the rod and adjustable longitudinally thereon, whereby the tension of the spring J may be adjusted and controlled to increase or decrease the force applied to the reciprocating rod by said spring.

An angular stay member G is secured to the upper swinging end of the door by screws or other suitable means, and has an opening in its horizontal portion for receiving a hook provided at the outer end of the reciprocating rod F. The length of the rod F is such that the spring J is placed under slight tension when the door is closed. It will readily be seen that, since the pivoted end of the housing is swingable about a point located some distance horizontally from the surface of the door, while the swinging hook end of the rod F is connected rather closely to the surface of the door, the spring pressed rod F acts at an angle with respect to the surface of the door and tends to constantly urge the door to closed position.

Further, since the pivot point for the housing D at the bolt B is positioned nearer the path of swing of the stay member G than is the axis about which the door swings as it is swung open, the rod F will be forced inwardly into the housing D as the door is opened and will place the spring J under still greater tension. Therefore, when the door is released the spring will act through the rod to move the door toward closed position. Such motion is assured by the angle at which the housing, spring and rod act on the door, such angle being determined by the horizontal length of the holder plate A.

From the foregoing, it will be seen that if the door is swung open past a plane at right angles with the door frame, the force impressed upon

the spring will cause the rod to urge the door toward further open position, since the angle of application of force to the door is reversed when the door passes a plane vertical to the door frame. The improved door holder can therefore be utilized to urge the door toward either an open or a closed position.

For snubbing or resisting the action of the spring J, the reciprocating rod F is provided on its inner end with a packing washer or piston H, which is secured to the rod by means of nuts threaded thereon, or in any other suitable manner. The piston H engages the inner wall of the bore of the housing as the rod is reciprocated therein and, since the pivoted end of the housing is closed by the cap C, the suction created within the housing as the piston moves away from the closed end will operate to slow or check the action of the spring urging the door closed.

Obviously, the door holder may be manufactured in sizes and styles to suit substantially any type or size of door desired. Also, it will be seen that the device is simple in construction and may be economically manufactured without the use of complicated machinery.

The foregoing description of the invention is explanatory only, and changes in the details of the construction illustrated may be made by those skilled in the art, within the scope of the appended claims, without departing from the spirit of the invention.

What I claim and desire to secure by Letters Patent is:

1. A door holder including, a holder member adapted to be secured to a door frame and project horizontally therefrom, a vertically disposed pivot member at the outer end of the holder member spaced from the surface of the door frame and lying in a plane extending through the door hinges vertically to the plane of the door frame, an elongate tubular housing swingably secured at one end to the pivot member and swingable through an arc of approximately 180 degrees thereon, an elongate reciprocating member telescoping the housing and adapted to have its outer end pivotally secured to the free side of a door, a helical coiled tension spring completely enclosed in the housing and surrounding the inner portion of the reciprocating member and having one end secured to the housing adjacent the outer swinging end thereof, a spring connecting and adjusting member threaded onto the inner end of the reciprocating member, the other end of the elongate helical coiled tension spring being secured to said spring connecting member under tension whereby the spring resists further telescopic movement of the reciprocating member into the housing and normally urges the reciprocating member outwardly from within the housing, the connecting member being adjustable on the reciprocating member for adjusting the force exerted by the spring, the pivot element on which the housing is swingably mounted being spaced from the plane of the sur-

face of the door a greater distance than the point of connection of the outer end of the reciprocating member with said door when the door is in the closed position, whereby the force of the tension spring is applied to the reciprocating member to normally urge the door toward closed position, and whereby the tension spring acts upon the reciprocating member to urge the door toward further open position when the door is swung open through an arc in excess of 90 degrees, the reciprocating member being movable freely with respect to the housing to permit the door to swing through an arc of approximately 180 degrees.

2. A door holder including, an elongate tubular housing, a plunger bar telescoping said housing and its outer end adapted to be pivotally connected to the free side of a door, a helical coiled tension spring completely enclosed within the housing and surrounding the plunger bar, said spring being secured at one end to the outer end of the housing, an adjusting nut threaded onto the inner end of the plunger bar and having the other end of the spring secured thereto so that the spring normally urges the bar outwardly of the housing, said nut being adjustable to vary the force exerted by the spring, means for connecting the projecting outer end of the plunger bar to a door, a holder plate adapted to be secured to a door frame and project horizontally therefrom and having an upright pivot pin at its outer end positioned in a plane extending vertically from the door frame through the door hinges, said pivot pin having the inner end of the housing pivotally secured and freely swingable in a horizontal plane thereon, the telescopic movement of the plunger bar into the housing terminating short of engagement of the bar with the inner end of the housing whereby the door may be swung through an arc of approximately 180 degrees and the spring will act upon the plunger bar to urge the door toward open position when the door is swung open in excess of 90 degrees, said spring acting upon the bar to urge the door toward closed position when the door is swung open less than 90 degrees.

ENOTH JACKSON BLACKMON.
